(57) **CLAIM**

The ornamental design for a locket, as shown and described.

DESCRIPTION

FIG. 1 is a perspective view of a locket showing my new design;

FIG. 2 is a front elevational view thereof;

FIG. 3 is a rear elevational view thereof;

FIG. 4 is a left edge view thereof;

FIG. 5 is a right edge view thereof;

FIG. 6 is a top plan view thereof; and,

FIG. 7 is a bottom plan view thereof.

The portion shown in broken lines in FIG. 1 is for information only and does not form a part of the claimed design.

The characteristic feature of the design resides in the specific location of the bale member in relation to the heart-shaped configuration of the locket.
